UNITED STATES PATENT OFFICE.

FREDRIC M. PARKER, OF WORCESTER, MASSACHUSETTS, ASSIGNOR TO
WILLIAM JAMES HOGG, OF SAME PLACE.

DESIGN FOR CARPET.

SPECIFICATION forming part of Design No. 25,680, dated June 23, 1896.

Application filed May 22, 1896. Serial No. 592,883. Term of patent 3½ years.

To all whom it may concern:

Be it known that I, FREDRIC M. PARKER, a citizen of the United States, residing at Worcester, in the county of Worcester and State of Massachusetts, have invented and produced a new and original Design for Carpets, of which the following is a specification.

My invention relates to a design to be worked into or upon carpeting or similar fabrics; and I do hereby declare that the drawing accompanying this specification gives and conveys to any one skilled in the art of carpet-weaving a clear understanding of the same that is sufficient to enable such persons to use my invention.

The said drawing is a face view of a carpet embodying my new design. The drawing illustrates a body and a border.

The body A is divided into irregularly-shaped panels by a connected chain of small floral and lozenge-shaped figures of "Indian" style. The panels are of three different shapes, and those of similar shape are situated horizontally and diagonally as to each other. In the panels are placed different figures, similar figures being in similar panels. In each of the largest panels is placed a figure of an irregular trefoil shape formed by narrow interlacing bands. In each of the next largest panels are placed two inverted figures of the shape known as "conventionalized Indian-palm leaves," formed by a dotted outline effect with diagonal bars crossing the center. Between these, lower down in the panel, are placed two interlacing links. Each of the smallest panels contains an Indian figure consisting of a flower-shaped base from

which rises a semicircle of small floral figures, a twisted stem protruding from the top, and oblique bars slanting downward right and left, filling the center space. Inclosing all these are two zigzag-shaped conventionalized half-leaves, connected at the bottom to the flower-shaped base, and a broken semicircle of small circular figures.

The border B consists of substantially the same figures and arrangement as the body. The inner edge is defined by a series of small conventionalized Indian-palm leaves similar to those in the body, but placed erect, and alternated by small conventionalized floral figures. The outer edge is characterized by interlacing figures similar to those of the body, alternated by large conventionalized Indian-palm leaves. Small figures having rounded outlines are placed one on each side of the conventionalized palm-leaves.

The colors employed for the different portions of this design may be varied to suit the convenience or taste of the manufacturer.

What I claim, and desire to secure by Letters Patent, is—

1. In a design for carpeting, the body A, substantially as shown.
2. In a design for carpeting, the border B, substantially as shown.
3. The design for carpets, consisting of the body A and the border B, substantially as shown.

FREDRIC M. PARKER.
